AUTOMATIC FREQUENCY CONTROL

Nelson P. Case, Great Neck, N. Y., assignor to
Hazeltine Corporation, a corporation of Delaware

Application July 22, 1936, Serial No. 91,864

6 Claims. (Cl. 250—20)

This invention relates to modulated-carrier signal receivers, and particularly to the control of the resonant frequency of tunable oscillation circuits of such receivers.

5 The invention is especially concerned with adjusting the resonant frequency of a tunable oscillation circuit of a signal receiver independently of its main tuning adjustment, and it is especially suitable for controlling the frequency of 10 the oscillation circuit of a superheterodyne radio receiver to maintain the intermediate-frequency carrier at a predetermined frequency for all tuning adjustments of the receiver.

In an oscillation circuit containing inductance 15 and capacitance elements, one of which is adjustable for tuning the circuit over a desired frequency range, it is frequently desired to adjust the resonant frequency of the circuit relative to the frequency selected by the main tuning element and independently of said element over a small fraction of the tuning range. Such an auxiliary adjustment is useful for various purposes. For example, it may be employed to facilitate the exact tuning of a superheterodyne receiver by controlling, within narrow limits, the 20 frequency of the oscillation circuit of the frequency changer in such receiver, independently of the main tuning means in said circuit and in response to departures of the intermediate-frequency carrier from a desired predetermined 25 value, in order to minimize such departures and ensure optimum fidelity of reproduction; or, such adjustment may be used to shift the intermediate-frequency carrier relative to the mean resonant frequency of an intermediate-frequency selector in order to adjust the selectivity of the 30 system.

It has heretofore been proposed to effect such frequency adjustment by connecting across the 35 oscillation circuit additional or auxiliary adjustable reactance means. However, in such a circuit, the reactance of the main tuning element varies over a wide range as this element is adjusted to tune the circuit over the range. The effectiveness of the auxiliary reactance means in 40 adjusting the resonant frequency of the circuit is ordinarily dependent on the relative magnitudes of its impedance and those of the main reactance elements of the circuit. Hence, the effectiveness of the auxiliary reactance means tends to vary with the frequency to which the 45 circuit is tuned. In order, therefore, to obtain equal adjustments of the resonant frequency of the circuit at all frequencies within its tuning range, different degrees of adjustment of the auxiliary 50

reactance means are ordinarily required. For satisfactory control of the frequency of a tunable oscillation circuit, either manual or automatic, it is essential that equal adjustments of the auxiliary reactance means effect equal adjustments of 5 the resonant frequency of the circuit for all frequencies within its tuning range. Furthermore, in the just described arrangements, the auxiliary reactance means tend substantially to limit the range of frequency over which the circuit can 10 be tuned.

It is a primary object of the present invention, therefore, to provide a novel improved system for adjusting the resonant frequency of a tunable oscillation circuit independently of the main 15 tuning means thereof.

It is a further object of the invention to provide a system of the character described, wherein equal adjustments of the frequency-adjusting means effect substantially equal adjustments of 20 the resonant frequency of the circuit for all frequencies within its tuning range.

It is a further object of the invention to provide a system of the character described, wherein in the tuning range is substantially unaffected by 25 the auxiliary tuning means.

It is a further object of the invention to provide, in a modulated-carrier signal receiver, an improved system of the character described, including means responsive to electrical conditions 30 at a given point in the receiver, such as departures of the intermediate-frequency from a predetermined value, for controlling the frequency-adjusting means to minimize deviations of such electrical conditions from their normal value. 35

In accordance with a preferred embodiment of the present invention, a modulated-carrier signal receiver includes an oscillation circuit having an adjustable condenser for tuning the circuit to any selected frequency of its tuning range. 40 Means independent of the main tuning condenser are provided for adjusting the resonant frequency of the circuit relative to the selected frequency over a small fraction of the tuning range of the circuit. This means includes an auxiliary 45 condenser connected in series with the main tuning condenser, and it may comprise an aligning or padding condenser for the circuit. There is also provided adjustable impedance means, comprising capacitive and resistive components and 50 effectively connected in parallel with the auxiliary condenser, which has such characteristics, relative to the constants of the oscillation circuit, that equal adjustments thereof effect substantially equal adjustments of the resonant fre- 55

quency of the oscillation circuit at all frequencies within its tuning range. Moreover, by virtue of the manner in which the auxiliary adjusting means is connected in the oscillation circuit, the tuning range of the circuit is substantially unaffected thereby. The frequency-adjusting impedance means may be adjusted manually or, as in the preferred embodiment illustrated, automatically in response to departures of the resonant frequency of the circuit from its normal value.

In the specific form of the invention herein-after described, the invention is employed in connection with the oscillation circuit of a frequency changer in a superheterodyne radio receiver for controlling the resonant frequency of the oscillation circuit and, hence, the intermediate frequency developed by the frequency changer. The receiver also includes means for developing a control bias voltage which corresponds in polarity and amplitude to frequency departures of the intermediate-frequency carrier from the normal frequency thereof, resulting from oscillator drift, mistuning of the receiver, or other causes. This voltage is utilized to control a tube simulating an adjustable reactance and constituting the adjustable auxiliary impedance of the oscillation circuit, thereby to effect an adjustment of the frequency of this circuit which shifts the intermediate frequency in a direction to minimize departures thereof from its normal frequency.

For a better understanding of the invention, together with other and further objects thereof, reference is had to the following description taken in connection with the accompanying drawing, and its scope will be pointed out in the appended claims.

In the accompanying drawing, the single figure is a circuit diagram, partly schematic, of a superheterodyne receiver embodying the present invention.

Referring now more particularly to the drawing, there is shown schematically a superheterodyne receiver including a tunable radio-frequency amplifier 10 connected to an antenna 8 and ground 9. Connected in cascade with the radio-frequency amplifier 10, in the order named, are a frequency changer indicated generally at 11, an intermediate-frequency amplifier 12, a detector and automatic amplification control or AVC supply 13, an audio-frequency amplifier 14, and a sound reproducer or loud-speaker 15. The frequency changer 11 is shown in detail and it, together with the parts of the system associated therewith which involve the present invention, will be hereinafter further described. It will be understood that several parts of the system which are illustrated schematically may be conventional in their construction and operation, the details of which are well known in the art, rendering description thereof unnecessary herein.

Neglecting for the moment the particular operation of the parts of the system involved in the present invention, the system above described includes all of the features of a conventional superheterodyne receiver. The operation of such a receiver being well understood in the art, detailed explanation thereof is deemed unnecessary. In brief, however, a desired modulated-carrier signal intercepted by the antenna is selected and amplified in the radio-frequency amplifier 10 and converted by the frequency changer 11 to an intermediate-frequency signal. This signal is selected and amplified by the intermediate-frequency amplifier 12 and translated therefrom

to the detector 13, wherein the audio frequencies of modulation are derived. The audio frequencies of modulation are amplified in the audio-frequency amplifier 14 and reproduced by the loud-speaker 15 in conventional manner. Biasing potentials developed by the AVC supply 13 are supplied to control the gain of one or more of the tubes of the intermediate-frequency amplifier 12, and, if desired, also to control the gain of the preceding stages of the system to maintain the amplitude of the signal output of the amplifier 12 within a relatively narrow range for a wide range of received signal amplitude.

Referring now more particularly to the portion of the system in connection with which the present invention is employed, the frequency changer 11 comprises a pentagrid oscillator-modulator tube 16 having its signal input grid coupled to the radio-frequency amplifier 10, and an oscillation circuit including an inductance 20 and a tuning condenser 21 in parallel. The oscillation circuit is coupled to the first or oscillator grid of the tube 16 by way of a suitable coupling condenser 22, and to the second grid or oscillator anode through a feed-back path comprising an inductance 24, coupled to the inductance 20, and a coupling condenser 25.

The condenser 21 is connected for unicontrol with the tuning condensers of the amplifier 10 in a conventional manner, as indicated by the broken lines U, and an aligning condenser 23 is connected in series in the oscillation circuit, serving to align the oscillation circuit with the tuned circuits of the radio-frequency amplifier 10, so that a substantially fixed intermediate frequency will be developed by the frequency changer as the tunable circuits are all simultaneously adjusted by the unicontrol means U to tune the circuits over their respective ranges.

A suitable biasing resistor 17 and by-pass condenser 17a are included in the cathode circuit of the tube 16, and a leak resistor 18 is connected between the oscillator grid and the cathode. Proper operating potentials are supplied to the screen from a suitable source, indicated at +Sc, and to the oscillator anode from a suitable source, indicated at +B, by way of a resistor 19. The frequency changer as thus far described comprises a substantially conventional circuit arrangement, the operation of which is well known.

In accordance with the present invention, for the purpose of adjusting the frequency of the oscillation circuit 20, 21 independently of the main tuning condenser 21, there is provided a tube 26 having an input circuit comprising in series a resistor 27, blocking condenser 28 and the inherent grid-to-cathode capacitance of the tube, which is indicated by dotted lines as a condenser 29, connected across the oscillation circuit, as shown. The blocking condenser 28 is sufficiently large as to have substantially no effect on the characteristics of the circuit at the oscillation frequencies, and the impedance of the resistor 27 is large relative to that of the grid-cathode capacitance at the oscillation frequencies. The output circuit of tube 26 is connected across the series-aligning condenser 23, the cathode circuit of the tube including a suitable source of biasing voltage, indicated at +C. The tube 26 is preferably of a high impedance type, such as a pentode, operating voltages being supplied to the screen from a suitable source, indicated at +Sc, and to the anode from a source, indicated at +B, by way of a resistor 30.

For the purpose of controlling the oscillation

frequency in accordance with deviations of the intermediate-frequency carrier from its normal value, due to oscillator drift, misadjustments of tuning, or other causes, so as to minimize such 5 deviations and ensure optimum fidelity of reproduction at all times, means are provided for developing a control voltage which varies in amplitude and polarity in accordance with such deviations and for properly applying this voltage 10 to the control grid of the tube 26 in order to effect the required frequency adjustments. These means preferably comprise a frequency discriminator and rectifier, indicated schematically at 32, coupled to the intermediate-frequency amplifier 15 12, and having its output circuit connected by way of a suitable filter, including a series resistor 33 and shunt condenser 34, and a resistor 31 to the control grid of the tube 26. The discriminator and rectifier 32 may be of any suitable type, various 20 practical arrangements for this purpose being well known in the art. For example, the discriminator-rectifier may comprise a circuit arrangement, such as is described in detail in British Patent No. 443,423, accepted February 25, 1936. 25 Preferably, however, this arrangement for providing the frequency control bias voltage will comprise a circuit arrangement similar to that disclosed in my copending application, Serial No. 72,532, filed April 3, 1936.

30 Referring now more particularly to the operating characteristics of the frequency control circuits, since the impedance of resistor 27 is high compared to that of the grid-to-cathode capacitance 29, the voltage across the capacitance 29 35 lags the voltage across the oscillation circuit. The circuit constants are so chosen that, at the high-frequency end of the tuning range, the voltage lag will be approximately 90 degrees. At the low-frequency end of the range the impedance of the 40 capacitance 29 increases relative to that of the resistor 27, so that the lag of the voltage across the capacitance 29 will be correspondingly less. The space current of the tube, being in phase with the tube input voltage, also lags the voltage 45 across the oscillation circuit in corresponding degree. It is to be noted, however, that the voltage across the condenser 23 is in phase opposition to the voltage across the oscillation circuit, so that the space current of the tube leads the 50 voltage across the condenser 23 and the tube simulates an impedance having capacitance and resistance components only, the value and character of which impedance varies in accordance 55 with the frequency of the oscillation circuit, and the value of which varies also in accordance with the grid-bias voltage applied to the tube.

By proper adjustment of the various circuit constants, the variations of the amplitude and 60 phase of the plate current of the tube 26 with respect to the oscillation voltage, as the oscillation circuit is tuned over its range, are controlled so that equal variations of the mutual conductance of the tube, resulting from adjustments of its grid-bias voltage, effect substantially equal 65 adjustments of the resonant frequency of the circuit for all frequencies of its tuning range.

70 This relation is possible because the tube 26 is connected across the aligning condenser 23, which is connected in series with the tuning condenser 21. The effectiveness of this aligning condenser is dependent upon the ratio of its impedance to that of the tuning condenser 21, which varies in a predetermined manner as the oscillation circuit is tuned over its range. Therefore, 75

if condenser 23, per se, were made adjustable for the purpose of effecting the auxiliary frequency adjustment, its effectiveness would vary inversely in accordance with the frequency to which the circuit was tuned. It will be understood that the 5 word "effectiveness" as here employed is intended to mean the frequency change in kilocycles of the oscillation circuit resulting from a given adjustment of the condenser 23. Obviously a given percentage frequency adjustment at a high 10 frequency constitutes a substantially greater adjustment in kilocycles than the same percentage frequency adjustment at a low frequency. Thus, the above-mentioned variation in effectiveness 15 of condenser 23 would be such that the percentage frequency change would be less at the higher frequencies than at the lower frequencies for a given capacitance adjustment. However, for initially aligning the oscillation circuit with the 20 tuned radio-frequency amplifier circuits, the condenser 23 ordinarily is of such size that its percentage frequency variation would not be at the proper rate to result in equal effectiveness, that is, equal frequency adjustments in kilocycles for 25 the same capacitance adjustment at different frequencies of the tuning range. In accordance with the present invention, therefore, there is provided an auxiliary tuning control means which, in the 30 illustrated embodiment, comprises the tube 26 and its associated circuits as described above, the 35 percentage frequency variation of which, with respect to the frequency to which the oscillation circuit is tuned, is correlated with the relative capacitances of condensers 23 and 21, so that an increment of control, while effecting different 40 percentage frequency adjustments of the oscillation circuit, effects the same frequency adjustment in kilocycles at all frequencies of the tuning range of the circuit. Furthermore, in the arrangement described having the output circuit 45 of the tube 26 connected across the relatively large aligning condenser 23 of the oscillation circuit, the tuning range of the circuit is not limited to an appreciable extent by the effective capacitance of the auxiliary tuning means. 45

In considering the operation of the system as a whole, it will be assumed that the receiver initially is exactly tuned to the desired signal frequency and the normal intermediate-frequency carrier is being developed by the frequency changer 11; that no bias voltage is developed by the discriminator and rectifier 32; and that the resonant frequency of the oscillation circuit is of a proper value to give the normal intermediate frequency, taking into consideration the effect of the 50 tube 26 with normal grid voltage applied. When, however, the intermediate-frequency carrier deviates from its normal frequency, due to mistuning of the oscillator with respect to the carrier wave of the desired signal, or other causes, a 55 bias voltage is developed by the discriminator and rectifier 32 having polarity and amplitude variable in accordance with the direction and amount of the deviation. This voltage being applied to the control grid of the tube 26 effects a variation 60 in the mutual conductance thereof, and hence a change in the amount of apparent capacitance and resistance provided thereby effectively in parallel with the condenser 23, so as to shift the 65 oscillation frequency in the proper direction to minimize the frequency deviation of the intermediate-frequency carrier and ensure optimum fidelity of reproduction. 70

While it is obvious that this invention is not restricted to an oscillation circuit or system em- 75

ploying circuit elements of any particular value, the following values were found to give satisfactory performance in a particular receiver:

5	Resistor 27	ohms	100,000
	Condenser 28	micro-microfarads	500
	Resistor 30	ohms	50,000
	Resistor 31	megohm	1/2
	Tube 26	type	6J7
10	Screen voltage	volts	106
	Cathode voltage	volts	4.7
	Grid-to-cathode capacitance 29	micro-microfarads	10
15	Tuning range of oscillation circuit 20, 21	kilocycles	802-1857

In the particular system referred to, for maximum grid-bias voltage of one polarity applied to the tube 26, specifically a grid-bias of -4.5 volts, the control effect on the oscillation frequency for 20 the various frequencies of the tuning range varied only within the range of +5.5 to +6 kilocycles, while for the maximum grid-bias voltage of the other polarity, +4.5 volts, the control effect varied only within the range of -4.5 to -6 kilocycles.

25 While there has been described what is at present considered to be the preferred embodiment of this invention, it will be obvious to those skilled in the art that various changes and modifications may be made therein without departing from the 30 invention, and it is, therefore, aimed in the appended claims to cover all such changes and modifications as fall within the true spirit and scope of the invention.

What is claimed is:

35 1. An oscillation circuit tunable over a range of frequencies and including an adjustable condenser for tuning said circuit to a selected frequency of said range and means, independent of said tuning condenser, for adjusting the resonant 40 frequency of said circuit relative to said selected frequency over a small fraction of said range, comprising an auxiliary condenser connected in series with said adjustable condenser, a vacuum tube having a phase-shifting input circuit coupled to said oscillation circuit and an output circuit connected across said auxiliary condenser, said tube having such characteristics relative to the constants of said circuits with which it is associated and being so connected to said oscillation circuit that its output circuit simulates an impedance having a capacitive component and that equal variations of the mutual conductance thereof effect substantially equal adjustments of the resonant frequency of said oscillation circuit 50 for all frequencies of said range, and means for adjusting the mutual conductance of said tube.

60 2. An oscillation circuit tunable over a range of frequencies and including an adjustable condenser for tuning said circuit to a selected frequency of said range and means, independent of said tuning condenser for adjusting the resonant frequency of said circuit relative to said selected frequency over a small fraction of said range, comprising an auxiliary condenser connected in 65 series with said adjustable condenser and a vacuum tube having an input circuit including phase-shifting means coupled to said oscillation circuit and an output circuit connected across said auxiliary condenser, said tube having such 70 characteristics relative to the constants of said circuits with which it is associated that its output circuit simulates an impedance having a capacitive component and that equal variations of the mutual conductance thereof effect substantially equal 75 adjustments of the resonant frequency of

said oscillation circuit for all frequencies of said range.

3. An oscillation circuit tunable over a range of frequencies and including an adjustable condenser for tuning said circuit to a selected frequency of said range and means, independent of said tuning condenser for adjusting the resonant frequency of said circuit relative to said selected frequency over a small fraction of said range, comprising an auxiliary condenser connected in series with said adjustable condenser, a vacuum tube having an output circuit connected across said auxiliary condenser, and a phase-shifting circuit comprising a high impedance resistance element and the inherent grid-cathode capacitance of said tube connected in series across said oscillation circuit, said capacitance having relatively low impedance at the oscillation circuit frequencies, said tube having such characteristics relative to the constants of said circuits with which it is associated that its output circuit simulates an impedance having a capacitive component and that equal variations of the mutual conductance thereof effect substantially equal adjustments of the resonant frequency of said oscillation circuit for all frequencies of said range.

4. An oscillation circuit tunable over a range of frequencies and including an adjustable condenser for tuning said circuit to a selected frequency of said range and means, independent of said tuning condenser for adjusting the resonant frequency of said circuit relative to said selected frequency over a small fraction of said range, comprising an auxiliary condenser connected in series with said adjustable condenser, a vacuum tube having an output circuit connected across said auxiliary condenser, and a phase-shifting circuit comprising a resistance element and the inherent grid-cathode capacitance of said tube effectively in series across said oscillation circuit, said tube having such characteristics relative to the constants of said circuits with which it is associated and being so connected therewith that its output circuit simulates an impedance having a capacitive component and said resistance and inherent capacitance being so related that equal variations of the mutual conductance of said tube effect substantially equal adjustments of the resonant frequency of said oscillation circuit for all frequencies of said range.

5. In a wave-signal-receiving system including a circuit tunable over a first range of frequencies, an oscillation circuit tunable over a second frequency range related to said first range and having an adjustable condenser for tuning to a selected frequency thereof, said oscillation circuit being adapted for unicontrol tuning with said tunable circuit, an auxiliary aligning condenser connected in series with said tuning condenser, and means, independent of said tuning condenser for adjusting the resonant frequency of said oscillation circuit relative to said selected frequency over a small fraction of its tuning range, comprising a vacuum tube having a phase-shifting input circuit coupled to said oscillation circuit and an output circuit connected across said aligning condenser, and control means for adjusting the grid-bias voltage of said tube to effect variations of the mutual conductance thereof in accordance with variations of the resonant frequency of said oscillation circuit, said tube having such characteristics relative to the constants of said circuits with which it is associated and being so

connected to said oscillation circuit that its output circuit simulates an impedance having reactance and resistance components only and that equal variations of the mutual conductance thereof effect substantially equal adjustments of the resonant frequency of said oscillation circuit for all frequencies of said range.

6. In a superheterodyne wave-signal-receiving system including frequency-changing means for deriving from any selected modulated-carrier signal within a wide range of frequencies a second modulated-carrier signal having a carrier normally of a predetermined frequency but subject to deviations within narrow limits upon mistuning thereof, an oscillation circuit having an adjustable condenser for tuning said circuit over a range of frequencies to a selected frequency, means, independent of said tuning condenser for adjusting the resonant frequency of said circuit relative to said selected frequency over

a small fraction of said range, comprising an auxiliary condenser connected in series with said adjustable condenser, a vacuum tube having a phase-shifting input circuit coupled to said oscillation circuit and an output circuit connected across said auxiliary condenser, said tube having such characteristics relative to the constants of said circuits with which it is associated and being so connected to said oscillation circuit that its output circuit simulates an impedance having a capacitive component and that equal variations of the mutual conductance thereof effect substantially equal adjustments of the resonant frequency of said oscillation circuit for all frequencies of said range, and means responsive to said frequency deviations for adjusting said mutual conductance so to vary the frequency of said oscillation circuit as substantially to reduce said deviations.

NELSON P. CASE. 20
